(57) **CLAIM**

The ornamental design for a carrier for containers, as shown and described.

DESCRIPTION

FIG. 1 is a front, top perspective view of a carrier for containers showing my new design.

FIG. 2 is a rear, bottom perspective view thereof.

FIG. 3 is a front elevation view thereof.

FIG. 4 is a rear elevation view thereof.

FIG. 5 is a right elevation view thereof; the left elevation view is a mirror image of the right elevation view.

FIG. 6 is a top plan view thereof.

FIG. 7 is a bottom plan view thereof; and,

FIG. 8 is a plan view thereof shown in an unfolded configuration.

All evenly-spaced broken lines are shown for the purpose of illustrating parts of the article as well as environmental subject matter and form no part of the claimed design.
